COMBINATION CIGARETTE PACKAGE
CASE AND OPENERClarence E. Blakely, Onawa, Iowa, assignor of
one-half to W. A. Blakely, Grant Center, Iowa

Application September 27, 1939, Serial No. 296,720

2 Claims. (Cl. 206—41.5)

My invention relates to a cigarette case.

An object of my invention is to provide a cigarette case which will normally enclose a package of cigarettes.

A further object of my invention is to provide a cigarette case which will allow the reception of a cigarette package, and which will during the reception thereof automatically tear away a certain portion in the top of the cigarette package to allow removal of cigarettes therefrom.

A further object of my invention is to provide a cigarette case which will accommodate varied sizes of cigarette packages.

A further object of my invention is to provide a positive shearing means for accomplishing the opening of the same.

A further object of my invention is to provide a covering member, and a further means allowing a forcing of the cigarettes out of the case.

A further object of my invention is to provide the above mentioned objects in a simple construction which can be manufactured at reasonable cost.

With these and other objects in view, my invention consists in the construction, arrangement and combination of the various parts of my device, whereby the objects contemplated are attained, as hereinafter more fully set forth, pointed out in my claims, and illustrated in the accompanying drawing, in which:

Figure 1 is a side elevation of the case showing a cigarette package therein,

Figure 2 is a substantially sectional view taken medially thereof,

Figure 3 is a sectional view taken along the lines 3—3 of Figure 2,

Figure 4 is a modification,

Figure 5 is a detail,

Figure 6 is a bottom view of the case, and

Figure 7 is a detailed section taken along the lines 7—7 of Figure 3.

I have used the character 10 to represent the side walls of the case which is made preferably of fairly thin metal and which includes one end wall 11, the other end being open as at 12. The bottom wall is indicated by the character 13 which includes the overlapping flanges 14 which are attached to the members 10 and 11. The bottom wall 13 includes the small beveled lip 15 for allowing convenient reception of the cigarette package. The side walls 10 include the cut out portions 16.

Hinged at 17 is the flap 18 which includes the side flanges 19 and the end flange 20. The end flange 20 includes the small depressed teat 21.

The top wall of the case is indicated by the character 22 and merges into the vertical portion 23. Attached at 24 to the side walls 10 are the blades 25 which include the sharp beveled edges 26, the blades 25 joining at 27 to the member 23 and flush with the bottom thereof and sloping rearwardly and terminating at the points 28.

The top wall 22 includes an integral bent portion 29 which continues into the portion 30 which is parallel to the wall 22 and which bends upwardly into the portion 33. The bottom wall 13 includes a circular opening 34. The case is used in the following manner. The cigarette package, which is indicated by the character 35 and which is ordinarily made of paper and which is enclosed with the usual Cellophane wrapper, is inserted in the end 12 of the casing and with the top wall of the package placed against the guide member 30. The package 35 is then pushed inwardly in the direction of the arrow 36a (see Fig. 3) and during such travel, the sharp edges 26 of the blades 25 will begin to slice through the upper paper and Cellophane layer of the package which is indicated by the character 36. A portion of this upper layer will abut against the vertical flange 23 and will curl up approximately in the manner as shown in Figure 2, and when the entire package is inserted within the casing as shown in Figure 2 also, the upper portion between the wall 11 and the flange 23 will be opened, and the cigarettes, which are indicated by the character 37, will then be readily accessible.

When the package is inserted the flap member or lid 18 is in the position as shown in Figure 1, which is the normally closed position of the case, and when it is desired to remove a cigarette or cigarettes, the lid 18 is swung over to the position as shown in Figure 2, and by pressing through the opening 34 against the bottom of the package 35, the cigarettes 37 will be thrust upwardly so that they can be readily grasped by the fingers. The small teat 21 assists in locking the cover 18 against the end wall 11. After the cigarettes above the opening 34 are removed, further cigarettes can be shaken down to this position and the same operation repeated.

After the package is used up, it is grasped by the fingers in the cut away spaces 16 and pulled outwardly in the direction of the arrow 38. When the package is inserted as explained herefore, the cut away spaces 16 also allow reception of the fingers to provide a convenient

placement of the package completely within the casing.

A slight modification is shown in Figure 4 wherein the double blade structure is replaced by a single blade such as 39 which extends from the point 40 to the point 41 as shown. In this type of structure the same operation will be performed when the package is thrust into the casing due to the slicing or shearing action of the blade 39, and it will be understood that any type of blade can be employed for this purpose. The case, by virtue of this construction, encloses the entire package in a neat and compact manner and will take care of the slight variation of different sized packages.

If desired, an additional clip such as indicated by the character 42 is bent over and attached at 43 to the rear 11 of the case (see Figures 1 and 6). In this form of construction the clip can be used to receive small match packets, since the flat rear of the packets can be slid beneath the member 42 and side wall 10 of the case. The member 42 can be made of spring steel or any other suitable material.

It will now be seen that I have provided a cigarette case which allows the reception of a cigarette package and which automatically tears away an upper corner of the same to allow removal of cigarettes from the package, and it will be seen further that I have provided a structure of this nature which is simple in construction.

Some changes may be made in the construction and arrangement of the parts of my invention without departing from the real spirit and purpose of my invention, and it is my intention to cover by my claims any modified forms of structure or use of mechanical equivalents, which may be reasonably included within their scope.

I claim as my invention:

1. A combination cigarette package case and opener comprising an enclosing case including an open end and a top wall, shearing means positioned adjacent said top wall for shearing away an upper portion of a cigarette package when inserted in said enclosing case, said shearing means including a pair of substantially triangular blade members attached to the side walls of the casing, a vertical flange terminating said blade members for receiving the cut portions of the package thereagainst, said casing including an end wall spaced from said vertical flange to provide an opening for removal of cigarettes after shearing of said package upper portion, said blade members having inward slicing edges, and said edges being joined at the mid-point of said vertical flange.
2. A combination cigarette package case and opener comprising an enclosing case including an open end and a top wall, shearing means positioned adjacent said top wall for shearing away an upper portion of a cigarette package when inserted in said enclosing case, said shearing means including a pair of substantially triangular blade members attached to the side walls of the casing, a vertical flange terminating said blade members for receiving the cut portions of the package thereagainst, said casing including an end wall spaced from said vertical flange to provide an opening for removal of cigarettes after shearing of said package upper portion, said blade members having inward slicing edges, and said edges being joined at the mid-point of said vertical flange,
3. A combination cigarette package case and opener comprising an enclosing case including an open end and a top wall, shearing means positioned adjacent said top wall for shearing away an upper portion of a cigarette package when inserted in said enclosing case, said shearing means including a pair of substantially triangular blade members attached to the side walls of the casing, a vertical flange terminating said blade members for receiving the cut portions of the package thereagainst, said casing including an end wall spaced from said vertical flange to provide an opening for removal of cigarettes after shearing of said package upper portion, said blade members having inward slicing edges, and said edges being joined at the mid-point of said vertical flange, said casing including a bottom wall having an opening positioned directly beneath said cigarette removing opening to cause removal thereof by manual pressure through said bottom wall opening.
